UNITED STATES PATENT OFFICE.

MARCUS BEBRO, OF KILBURN, COUNTY OF MIDDLESEX, ENGLAND.

TICKET PRINTING AND NUMBERING MACHINE.

SPECIFICATION forming part of Letters Patent No. 248,275, dated October 18, 1881.

Application filed October 23, 1880. (No model.) Patented in England May 11, 1880.

To all whom it may concern:

Be it known that I, MARCUS BEBRO, the above-named petitioner, a resident of Canfield House, Priory Road, Kilburn, in the county of Middlesex, London, England, have invented 5 new and useful improvements in mechanism or apparatus to be employed for numbering checks, tickets, and other similar and like articles progressively and consecutively, of which 10 the following is a specification.

The object of this invention, for which I have obtained Letters Patent in Great Britain, dated May 11, 1880, No. 1,917, is to produce a compact machine which will consecutively number, 15 print, and perforate tickets, checks, labels, or the like, in a simple, effective, and expeditious manner; and the improvements consist, first, in the novel and peculiar construction and arrangement of a cylinder or cylinders containing 20 disks provided with numbers around their peripheries so disposed and actuated that each number, from cipher to nine, will give its impression with each revolution of the cylinder or cylinders, and the forward or higher numbers 25 will, after the first revolution, through the medium of suitable gearing, be brought successively into action in proper consecutive order, at times when the changes take place—viz., from the numerals to the tens, then to the hundreds, then to the thousands, and so on.

The invention consists, secondly, in adapting the before-mentioned continuous consecutive numbering cylinder or cylinders to a machine designed for printing continuously tickets, 35 checks, labels, and the like, and combining in one machine such numbering-cylinders with printing-rollers, or rollers carrying stereotype-plates, which will print upon both sides of such running length of paper subject-matter which, 40 with the numbers consecutively printed thereon, form a length of tickets which are divided one from the other by perforations previous to the length of printed paper being run onto a receiving-spool.

The invention consists, thirdly, in providing 45 some of the numbering-disks with movable type, and, in combination therewith, of mechanism to automatically retract or project said type from or to the printing-surface, for purposes 50 hereinafter explained.

The invention consists, fourthly, in devices

for throwing the numbering-disks out of gear, to enable the operator to adjust them to print from any desired number; and the invention consists, lastly, in certain details of construction and arrangement of the mechanism, all as hereinafter fully described.

In order that the invention may be well understood, I will describe the same in detail, reference being had to the accompanying drawings, in which—

Figure 1 represents, in front elevation, a general view of the improved number and subject-matter printing-machine. Fig. 2 represents a plan, partly in section, of Fig. 1 through the line *z z*. Fig. 3 represents an end elevation of the same. Fig. 4 represents a section of Fig. 1 through the line *y y*. Fig. 5 represents a longitudinal section of a part of one of the duplicate numbering-cylinders, taken through the line *x x* of Fig. 6. Fig. 6 represents, in front elevation, one of the duplicate cylinders I employ for printing consecutive numbers upon the running length of paper. This view shows the arrangement of gearing 75 employed for effecting the changes in the numbers. Fig. 7 represents a similar view of the opposite side of the numbering-cylinder. Fig. 8 represents the means employed for throwing the lock-disks, giving the changes to the numbering-disks, into and out of gear, for the purpose of enabling the operator at any time to adjust the numbering-disks so as to print the tickets consecutively forward from zero or from any advanced number. Fig. 9 represents 85 a side elevation of the same. Figs. 10 and 11 represent, respectively, a front elevation and side section of the means I adopt for placing certain of the types on the several numbering-disks into and out of position for printing when 90 required at the times the changes are made. Fig. 12 is a side elevation, and Fig. 13 a front elevation, of one of the disks that carries fixed numerals; and Fig. 14 is a vertical longitudinal section of one of the numbering-cylinders 95 complete.

The mechanism is mounted upon a suitable frame, *a*, and driven by a train of gearing, *E*, from any convenient or desired prime motor; and the machine is composed, preferably, of two numbering-cylinders, *A A*, combined with printing and perforating devices, hereinafter

described. These numbering-cylinders A A are mounted each upon a shaft, *b*, and being both alike in construction and operation, the description of the construction and operation 5 of one of them will be sufficient to enable those conversant with this class of machines to fully understand the same.

The cylinder A is composed of two disks, *c c'*, both provided with bearings for a series of 10 (preferably five) shafts, *d*, each carrying three numbering-disks, B C D, and suitable gearing, *h B' C' C² D'*. The disk *c'* also carries a ring, *k*, in which bearings are formed for a series of shafts, *m*, corresponding in number to that of 15 the shafts *d*, and carrying suitable gearing, *B² B³ C³ D²*. The disk *c* also carries fixed numerals, from 0 to 9, and, as there are two numbering-cylinders, A, employed, the disk *c* of 20 one of the cylinders carries the even numerals and that of the other cylinder the odd numerals, as shown at *g* in Figs. 12, 13, and 14, the disk *c* in the former two figures carrying the even numbers from 0 to 9 or 0 2 4 6 8, and the disk *c* in the latter figure being provided with 25 the odd numerals, or 1, 3, 5, 7, and 9.

Referring more particularly to Figs. 5 and 14, the operation of the numbering-cylinders is as follows: *e* is a single-toothed disk, which is stationary and forms part of a square journal, *f*, fixed to the framing *a*. Supported in 30 this fixed journal and passing through the fixed disk *e* is the shaft *b*, to which are keyed the disks *c c'*, carrying the type-numbering disks B C D and the gearing B' C' C² D'. The type-disks B C D are all provided with printing-numbers around their peripheries, commencing with cipher and ending with nine, each disk having an independent or separate motion around its axis *d* transmitted to it 35 and governed by the gearing B', C', C², D', *h*, and *e*. The disks *c c'* are fixed to and revolve with the shaft *b* as well as the numbering-disks D C B, and the gearing that serves to bring said disks D C B into proper position for 40 delivering their numbers consecutively and progressively to a running continuous length of paper. With each revolution of the shaft *b* and disks *c c'* the fixed numerals *g* deliver their 45 numbers in consecutive order from 0 to 9. As soon as the 9 is printed the tooth of the fixed disk *e* gears with and imparts one-tenth of a 50 revolution to the lock-disk *h*, and through the latter and the shaft *d* this one-tenth of a revolution is communicated to the disk B, printing the tens, and to the single-toothed disk B', 55 said disks B B' and lock-wheel *h* being rigidly mounted on shaft *d*.

When the disks B and B' have made one 60 complete revolution the tooth of the latter will have given one tenth of a revolution to the lock-wheel B², which latter communicates a like movement to the spur-wheel B³. Said wheels B² B³ are rigidly connected together and rotate freely upon their fixed stud or shaft 65 *m*. The spur-wheel B³ communicates this tenth of a revolution to the spur-wheel C', the single-

toothed disk C², and the numbering-disk C, to print the hundreds, said numbering-disk C being connected with the spur-wheel C' and disk C² by the sleeve *c²* and its collar or flange. 70

At each complete revolution of the numbering-disk C and the single-toothed disk C² the tooth of the latter gears with the lock-disk C³ and imparts thereto and to the wheel D² one-tenth of a revolution, both being rigidly connected. 75 This tenth of a revolution is communicated to the spur-wheel D' and numbering-disk D, (with which the spur-wheel D' is rigidly connected by means of the sleeve *d²*), to print the thousands. 80

It will thus be seen that at each complete revolution of the shaft *b* the fixed numerals on the disk C will be printed in consecutive order and each numbering-disk B C D of the five sets will be brought into position to consecutively print, first, the tens, then the hundreds, and then the thousands. 85

In order to prevent the ciphers printing only at the times at which they are required, I prefer to adopt the method shown at Figs. 10 and 90 11. In these figures the type representing the ciphers are made of separate pieces *i*, which are placed in grooves in the printing-disks, in which they can slide, so that when they are not required to print each sliding type is held down 95 below printing-surface by means of the projecting pins *i'*, the last one of which is held down by an inclined projecting surface, *i²*, fixed to the disks *c*. This inclined surface *i²*, when the type-disks are at zero, keeps the whole series of pins and sliding cipher-type in their depressed position consequent upon the pins being then in line and resting one upon the other, each pin of the numbering-disks C and D being provided with an inclined surface-piece of metal, 100 105 which is so arranged that the pin holding down the cipher of the ten-disk B is released from under the incline of the disk C immediately the said disk B receives its first tenth of a revolution, the position for printing when released 10 being assumed by means of the spring *i¹*. The same action takes place successively with each of the other disks immediately they receive their first tenth of a movement in manner hereinbefore described. On the highest number 115 of the combined disks being delivered, the stud or pin on the cipher of the disk D passes under the fixed incline surface *i²* of the disk *c*, and so becomes depressed, which action, as the pins are then in a line resting on each other, 120 causes them to be simultaneously depressed, so as to assume their lowest position, at which time the printing-disks are again in position for a fresh start.

If at any time after the machine has delivered a number below the maximum amount it is capable of printing it should be necessary to start at zero, I prefer to adopt the method shown at Figs. 8 and 9 of the drawings, in which *k* is a ring or circular piece of metal let 130 into the disk *c*. Said ring forms the bearing or support for the gearing revolving on the

fixed studs *m*, and as such gearing is placed in a position concentric to the wheels and disks with which they gear a slight movement to the left would throw the whole series out of gear; 5 and in order to effect this with facility fingers *l l*, projecting from the ring *k*, are provided. These fingers contain a slot or slots, through which studs project, so that when the handles *n n* are taken hold of and forced to the left the 10 extent of motion is determined which will throw the wheels out of gear, and so relieve the type-numbering disks, at which time they can be placed so as to commence printing the numbers at zero or from any other number at which it 15 would be requisite to start.

One or more type-numbering cylinders may be employed, preferably two, as shown, for printing numbers continuously and consecutively, both of which are exactly duplicates, one 20 being designed for printing the odd and the other the even numbers.

The type printing the numerals are fixed, as shown at *g*, Fig. 3, to the revolving disks *c*, the numbers in advance being printed by the type-numbering disks *B*, *C*, and *D*, as they are intermittently and successively caused to revolve around their axis in manner as hereinbefore described—that is to say, after the numerals have been delivered on the completion of the 30 first revolution. The numbering-disks *B*, as in manner described, are brought intermittently into action to print the tens until the number 99 has been printed off, at which time the disks *C* come into action and print the 35 hundreds up to the number 999, at the completion of which the disks *D* print the thousands up to the number 9,999, on the completion of which and immediately the last number is delivered the numbering-disks assume their 40 first position, placing the numbers at zero. The ciphers of the disks *B*, *C*, and *D*, when arriving at this position, are automatically depressed or lowered, as shown and described at Figs. 10 and 17 of the drawings.

45 The action of the numbering-disks, in combination with the rollers printing the subject-matter upon the running strip of paper, will now be understood on reference to the drawings.

50 *a a* is the framing of the machine supporting the printing-rollers and apparatus, hereinafter described, necessary for printing, numbering, and perforating on a continuous strip or length of paper, tickets, checks, labels, or the like.

55 A spool or roller, *o*, containing the blank roll of paper, card-board, or other material to be printed on, is mounted in suitable bearings, *p*. One end of such strip or length of paper is then passed in the direction indicated by arrows

60 between a first set of printing-rollers, *q q'*, *q* being the printing-roller and *q'* the impression-roller. The strip of paper receives from these rollers subject-matter on its front side. Passing on, it next receives at equal distances apart, 65 and in register with the subject-matter previously printed thereon, numbers in consecutive

order from the two cylinders, *A* and *A'*, the consecutive and progressive order of printing such numbers on the running length of paper being effected in manner as hereinbefore referred to. The upper surface of the paper as it is thus printed upon passes round the heated cylinder *r*, where the ink is dried, so as to prevent any "set-off" on the impression-roller *s*, between which and the type-roller *s'* it next 70 passes, and which print in register on the back of the length of paper subject-matter, advertisements, designs, devices, and the like.

t t are the perforators which divide the length of paper into tickets. *v v v v v* are inking-troughs, from which the ink is uniformly distributed to the type by the rollers *x*.

The machine is driven by the pulley *w* and gearing *E E*.

Having now described my invention, what I 85 claim is—

1. In a machine for consecutively numbering tickets, labels, checks, &c., upon a running strip of paper, printing subject-matter upon both sides thereof, and perforating said strip into 90 given lengths, the combination of the following elements, to wit: the spool *o*, the type-rolls *g* *s'*, the numbering-cylinders *A* *A'*, with their numbering-disks *D C B* *c*, and suitable impression-rolls, the drying-roll *r*, perforators *t t*, 95 receiving-spool *q*, inking mechanism *v x*, and the operating mechanism for said devices, all arranged, constructed, and operating in the manner and for the purpose substantially as specified.

100 2. In a machine for consecutively numbering tickets, labels, checks, &c., a continuously-rotating numbering-disk, *c*, in combination with a series of sets of numbering-disks, *D C B*, arranged in concentric order upon and rotating with said disk *c*, and mechanism, substantially such as described, for imparting to said series of sets of numbering-disks an independent intermittent rotation, substantially as described, for the purpose specified.

110 3. In a machine for consecutively numbering tickets, labels, checks, &c., a continuously-rotating numbering-disk, *c*, provided with fixed type, in combination with a series of sets of numbering-disks, *D C B*, provided with movable type arranged in concentric order upon and rotating with said disk *c*, mechanism, substantially such as described, for imparting an independent intermittent rotation to the several sets of disks *D C B*, and mechanism, substantially such as described, for automatically retracting or projecting the movable type to or from the face of said disks, substantially as and for the purpose specified.

120 4. The combination, with the disks *D C B*, 125 having movable type *i*, of mechanism, substantially as described, to automatically depress said type below the printing-face of said disks and to release the same automatically, in the manner and for the purposes substantially as 130 shown and described.

5. The combination of the disks *D C B*, their

movable type i , the inclines i^2 , the pins i' , and the disks e , substantially as described, and for the purpose specified.

6. The combination of the disks D C B, the movable type i , the inclines i^2 , pins i' , springs i^4 , and the disk e , substantially as described, and for the purpose specified.

7. The combination, with the disks B e , the shafts d , and toothed disks h , of the driving-shaft b and toothed disk e , all arranged and operating in the manner and for the purpose specified.

8. The combination of the disk e , carrying fixed numerals, the numbering-disk B, its single-toothed disk B' , the lock-wheel B^2 , the spur-wheels $B^3 C'$, and the numbering-disk C, with the lock-wheel h , single-toothed disk e , and the shaft b , substantially as described, for the purpose specified.

9. The combination of the disk e , carrying fixed numerals, the numbering-disk B, its single-toothed disk B' , the lock-wheel B^2 , the spur-wheels $B^3 C'$, the single-toothed disk C^2 , lock-

wheel C^3 , spur-wheels $D' D^2$, and the numbering-disk D, with the lock-wheel h , single-toothed disk e , and the shaft b , substantially as described, for the purpose specified.

10. The combination of the disk c' , carrying the ring-plate k , and mechanism, substantially such as described, to impart to said plate a partial revolution, and the shafts m , carrying the gearing $B^2 B^3 D^2$, with the gearing $B' C' C^2 D'$, substantially as and for the purpose specified.

11. The combination, with the disks D, C, B, and e and the shafts d , and toothed disks $B' C' C^2 D'$, of the disk k , having fixed studs m , the slotted levers l , carrying handles n , and the guide-pins n' , substantially as described.

In witness that I claim the foregoing I have hereunto set my hand this 20th day of September, 1880.

MARCUS BEBRO.
